(57) **CLAIM**

The ornamental design for a toddler's drinking straw as shown and described.

DESCRIPTION

FIG. 1 is a top plan view of a toddler's drinking straw, with an aperture of the straw pointed to the right, showing my new design;

FIG. 2 is a top plan view, with an aperture pointed to the left;

FIG. 3 is a left side elevation view;

FIG. 4 is a right side elevation view;

FIG. 5 is a rear elevation view;

FIG. 6 is a front elevation view;

FIG. 7 is a top perspective view;

FIG. 8 is a left side elevation view shown in use with environment; and,

FIG. 9 is a perspective view shown in use with environment. The broken lines in FIGS. 8 and 9 illustrate environment that forms no part of the claimed design.
